OF MARYSVILLE, KANSAS

TIE PLATE

Application filed June 18, 1930. Serial No. 462,040.

This invention relates to rail tie plates, and has for an object the provision of a simple tie plate provided at the outer side of its rail seat with spike holes and with a longitudinal 5 rib forming an inwardly facing shoulder for contact with the base flange of the rail, said spike holes being entirely outwardly of the plane of said shoulder to prevent the shanks of the spikes from being "rail-cut" or worn 10 and weakened by outward pressure and vertical rubbing of the base flange of the rail thereon.

A further object is to extend the rib across the spike holes at the inner side of the latter 15 to form elevated bearings for the inner sides of the spike heads whereby the latter are held slightly spaced from the base flange of the rail to permit limited vertical movement of the rail, and to minimize pulling action of the 20 rail on the spikes and consequent loosening of the spikes and damage to the tie.

A still further object is to provide the under side of the tie plate with anchoring ribs having rounded edges to embed themselves 25 in the surface of the tie without material injury to the tie, but so as to effectively prevent creeping of the tie plate.

Another object is to form the under side of the tie plate with shallow upwardly arched 30 portions between the anchoring ribs so as to provide clearance to accommodate any material of the tie crowded therein due to embedding of the ribs in the tie, thereby more securely anchoring the tie plate against creeping.

The invention consists in the novel features and construction hereinafter more fully described, shown in the accompanying drawings, and claimed.

In the drawings:

Figure 1 is a top plan view of a rail, together with a tie plate embodying the present invention.

Figure 2 is a transverse section on line 2—2 of Figure 1, together with a tie having the tie plate secured thereon.

Figure 3 is a bottom plan view of the tie plate shown in Figure 1, drawn on a reduced scale.

Figure 4 is a top plan view of a modified

form of tie plate embodying the present invention.

Figure 5 is a transverse section on line 5—5 of Figure 4; and

Figures 6 and 7 are bottom plan views 55 drawn on a reduced scale and showing further modifications of the arrangement of anchoring ribs on the under side of the tie plate.

Referring in detail to the drawings, 5 indicates a track rail having the usual tread 60 portion 6 and base flanges 7. The rail 5 is supported on a wooden tie 8 and secured to the latter by spikes 9 whose heads 10 overlie the margins of the base flanges 7 of the rail. The present tie plate is indicated at 11 and 65 is interposed between the rail and the tie in the usual way.

As shown, the tie plate 11 has the general form of a flat plate with an intermediate top surface portion 12 forming the rail seat and 70 provided at the outer side of said seat with an upstanding longitudinal rib 13 shaped to form an inwardly facing shoulder for contact with the edge of the adjacent outer base flange of the rail to resist outward lateral 75 pressure on the latter. The tie plate is provided with any desired number of holes for spikes, certain of the holes being located at the outer side of the rail as at 14, and the other holes being located at the inner side thereof 80 as at 14a.

The holes 14 are located entirely outwardly of the plane of the shoulder formed by the inner wall or face of the adjacent rib 13 to prevent the shanks of the spikes driven 85 therethrough from being "rail-cut" or worn and weakened by the outward lateral pressure and vertical rubbing of the adjacent base flange of the rail thereon. The rib 13 is extended across the inner sides of the spike 90 holes 14, as at 17, and may be of a height to form elevated bearings for the inner sides of the heads of the adjacent spikes, whereby said spike heads are held slightly spaced from and above the adjacent base flange of the 95 rail to permit limited vertical movement of the rail and to minimize pulling action of the rail on said spikes and consequent damage to the tie. The clearance between the spike heads and the base flanges of the rail is clear-

- ly shown in Figure 2. The tie plate of Figure 1 is shown as further provided with an up-standing longitudinal rib 13' forming an inwardly facing shoulder for contact with the 5 edge of the adjacent inner base flange of the rail, the said rib being extended across the inner sides of the spike holes 14a as at 17a and being of a height to form elevated bearings for the inner sides of the heads of the 10 adjacent spikes. However, the ribs 13' may be omitted, and the spike holes 14a may be arranged so that the shanks of the spikes driven therethrough will engage the edge of the inner base flange of the rail. Also, while 15 the ribs 13 and 13' are shown as extending the entire length of the tie plate, either or both may consist of short rib sections 13a merely extending along the inner sides of the adjacent spike holes 14 and 14a. 20 The under side of the tie plate may be provided with anchoring ribs 18 having rounded edges. The ribs 18, so formed and arranged, will embed themselves in the surface of the tie without material injury to the tie, but 25 so as to effectively prevent creeping of the tie plate. The ribs 18 in Figures 1 to 3 inclusive have parallel angularly extending portions, while those in Figure 7 are straight and parallel and extend in one direction. If 30 desired, the under side of the tie plate may be formed with upwardly arched portions 19 between the anchoring ribs 18 so as to provide clearance to accommodate any material of 35 the tie crowded therein due to embedding of the ribs 18 in the tie. This permits the ribs to very freely embed themselves in the tie to securely anchor the tie plate against creeping. 40 In Figures 4 and 5, short upstanding rib sections 13a are provided at the inner side 45 of the rail seat 12 and extend across the adjacent spike holes 14a to protect the adjacent spikes from wear. The arrangement of ribs to contact both base flanges of the rail provides for very firmly holding the rail in place 50 and minimizing creeping of the rail. In this instance, the ribs are low in height so that the heads of the spikes overlie and contact the base flanges of the rail to firmly hold the latter against tilting. Holes 20 may be provided 55 in the opposite sides of the tie plate to receive screw spikes or nails 21 for anchoring the tie plate to the tie against rattling. However, the holes 20 may be omitted. 60 Other minor changes are contemplated 55 within the spirit and scope of the invention as claimed. 65 What we claim as new is: 70 A tie plate provided at the outer side of the rail seat with spike holes and with a rib 60 forming an inwardly-facing shoulder for contact with the adjacent outer base flange of the rail, said spike holes being located entirely outwardly of the plane of said shoulder, said rib being extended across the inner side 65 of said spike holes and being of a height to 75 form elevated bearings to contact and hold the inner side of the adjacent spike heads slightly spaced from and above the adjacent base flange of the rail. 80 In testimony whereof we affix our signatures. 70 CHARLES EDWARD ENNIS.
